FILM HOLDING BOX

Samuel Pavelle, White Plains, N. Y., assignor, by mesne assignments, to Technicolor New York Corporation, a corporation of Delaware

Application March 21, 1955, Serial No. 35,139

Term of patent 14 years

(Cl. D58—12)

Fig. 1.

Fig. 2.

Fig. 3.

The characteristic features of my design for the film holding box disclosed reside in in the beading on the top thereof as shown.

I claim:

The ornamental design for a film holding box, substantially as shown and described.
